UNITED STATES PATENT OFFICE.

JAMES WEIR, OF PAISLEY, SCOTLAND.

MARINE-ENGINE GOVERNOR.

SPECIFICATION forming part of Letters Patent No. 657,208, dated September 4, 1900.

Application filed May 15, 1900. Serial No. 16,769. (No model.)

To all whom it may concern:

Be it known that I, JAMES WEIR, a citizen of the United Kingdom of Great Britain and Ireland, residing at 48 Love street, Paisley, 5 county of Renfrew, Scotland, have invented certain new and useful Improvements in Marine-Engine Governors, of which the following is a specification.

This invention relates to marine-engine governors of the class wherein the throttle-valve in the steam-pipe is controlled to prevent racing of the engines by the movement relatively to the ship of a pendulum connected to operate said valve and so weighted as 15 to insure its remaining practically plumb in heavy seas.

The invention has for its object to provide simple and efficient devices for so connecting the pendulum to the throttle-valve that the latter is more or less closed when the vessel's stern rises out of the water, while on the greater immersion of the stern and propeller the pendulum is prevented from acting on the throttle-valve. To that end the pendulum is attached to and suspended from a disk or strap centered upon a stationary disk secured to a carrying-bracket, the disks being adjustable upon each other in order to allow of the pendulum finding its plumb irrespec- 25 tive of the manner of loading the vessel. On the pivoted disk is adjustably secured a lever connected by a rod or like means to the lever on the throttle-valve spindle, and when the pendulum swings relatively to the vessel 30 as it pitches forward and the stern rises the lever on the pivoted disk acts on the throttle-valve to partially close it.

In the accompanying drawings, which illustrate the invention, Figure 1 is an elevation 40 of my improved marine-engine governor, showing its connection to the throttle-valve in the steam-supply pipe of an engine. Fig. 2 is a vertical section at right angles to Fig. 1, and Figs. 3 and 4 are details of the gover- 45 nor hereinafter particularly described.

To the pendulum-rod A, carrying an adjustable weight B at its lower end, I secure at the upper end thereof a disk C, formed with a flange C'. This disk C is centered 50 upon and arranged to turn freely at its center about a pin D', formed on or secured to one face of a stationary disk D, around the

outer periphery of which the flange C' of the disk C also bears, the stationary disk having also projecting from its other face a stud D², 55 by which it is secured to a carrying-bracket E, bolted to any convenient part of the engine-room. The stationary disk D is formed with a slot D³, carrying two pins F F', whose position may be adjusted in said slot D³, so that as the 60 pendulum oscillates the pins come sooner or later into contact with a web C² on the pivoted disk C to limit the travel or motion of the disk C upon the pin D' and outer circumference of the stationary disk D, whereby the complete 65 opening or the entire or partial closing of the throttle-valve G on the steam-supply pipe I is controlled. The pin F is preferably so positioned in the slot D³ of the stationary disk D as to bear against one side of the web C² 70 when the plumb of the pendulum is found, which will naturally vary in relation to its bracket E, according as the ship is loaded heavily or lightly forward. The relative movement between the pendulum and the 75 ship when the latter pitches is transmitted to the throttle-valve G from a lever H, which is centered on the pin D' of the stationary disk D and secured to the pivoted disk C by a screw-pin H', passing through said lever. 80 This screw-pin H' is entered in one of a series of holes c (shown particularly at Figs. 1 and 3) in the pivoted disk C, which holes admit of the lever H being secured in either of the three positions shown in full and dotted lines 85 at Fig. 1 in order to suit the requirements of the connections between the lever H and the spindle G' of the throttle-valve G.

Between the bearing-surfaces of the disks C and D balls may be inserted to reduce friction, 90 and the pendulum may be jointed athwart ships in order to take the strain off the axis of the pendulum-disk.

Owing to the sensitiveness of the pendulum action and the above-described arrangement 95 of disks for allowing the pendulum to find its plumb, a governor is provided, which speedily and effectually prevents "racing" of the engines.

Suitable springs or buffers may be used in 100 connection with the pendulum, so as to absorb the shock or jar which would occur when the ship pitches.

Having now described the invention, what

I claim, and desire to secure by Letters Patent, is—

1. In a marine-engine governor, the combination with a stationary disk secured upon a fixed center, of a weighted pendulum attached to a disk or strap fitted to turn about the axis of the stationary disk and having secured upon its axis a lever connected to the throttle-valve spindle of the engine.
2. In a marine-engine governor, the combination with a stationary disk secured to a carrying-bracket, of a pivoted disk fitted to turn about the axis of the fixed disk and carrying a weighted pendulum, a slot in the fixed

disk, stop-pins adapted to be secured in any position in said slot, a web in the pivoted disk designed to limit the extreme travel of the pivoted disk by contact with said pins, and a lever adjustably secured to the pivoted disk and connected to the throttle-valve spindle of the engine.

In witness whereof I have hereunto set my hand in presence of two witnesses.

JAMES WEIR.
